UNITED STATES PATENT OFFICE.

CHARLES C. PFEIFFER, OF WESTFIELD, NEW JERSEY, ASSIGNOR TO KNOBURN PRODUCTS CORPORATION, OF HOBOKEN, NEW JERSEY, A CORPORATION OF NEW JERSEY.

FIREPROOF DOOR.

REISSUED

Application filed May 23, 1924. Serial No. 715,270.

To all whom it may concern:

Be it known that I, CHARLES C. PFEIFFER, a citizen of the United States, and a resident of Westfield, county of Union, and State 5 of New Jersey, have invented certain new and useful Improvements in Fireproof Doors, of which the following is a specification.

This invention relates to doors and particularly to fireproof doors of the type in 10 which a wooden core or body is covered with a metallic sheathing.

The invention has for its salient object to provide a door construction of the type 15 specified that will be strong and serviceable and can be manufactured at a minimum labor cost.

Another object of the invention is to provide a door structure having the metallic 20 covering so mounted and secured over the core or body that the several parts of the covering or sheathing can be easily and readily connected together and will be securely held in position.

Further objects of the invention will appear from the following description taken 25 in connection with the drawings which form a part of this application and in which,

Fig. 1 is an elevational view of a door 30 constructed in accordance with the invention.

Fig. 2 is a longitudinal sectional elevation 35 of the structure shown in Fig. 1.

Fig. 3 shows the construction of the core 40 or body of the door and one method of securing the parts together.

Fig. 4 is an enlarged detail section taken substantially on line 4—4 of Figs. 2 and 5.

Fig. 5 is a detail sectional elevation taken 45 substantially on line 5—5 of Figs. 1 and 4.

Fig. 6 is a sectional elevation taken substantially on line 6—6 of Fig. 1.

Fig. 7 is a sectional elevation taken substantially on line 7—7 of Fig. 1, but showing 45 the construction on an enlarged scale.

Fig. 8 is a perspective detail view showing the construction of a corner between one of the stiles and a rail, the parts being shown separated for clearness.

Fig. 9 is a perspective elevation of the structure shown in Fig. 8, the various parts being shown as joined together.

Fig. 10 shows the construction of the

sheathing or metallic covering for the base shown in Figs. 8 and 9.

Fig. 11 is a perspective elevation showing the metallic sheathing for one of the stiles.

Fig. 12 is a perspective elevation showing the sheathing for one of the rails.

Fig. 13 is a perspective elevation showing one of the connectors for joining the sheathing of a stile and a rail, and

Fig. 14 is a sectional elevation taken substantially on line 14—14 of Fig. 1.

The invention briefly described consists of a door comprising a wooden core or body, the body being covered by a metallic sheathing. The sheathing is formed of several sections which are bent to shape and are then superimposed on the body, the various parts or sections of the sheathing being joined together and certain of the joints between the sheathing sections overlapping and bridging joints between the body portions. The details of the various joints have been worked out in a novel manner and will be clear from the following description.

The invention may be utilized in connection with any desired form of door but in the drawings the door is illustrated as having stiles 20, end rails 21 and an intermediate rail 22.

The stiles 20 as shown particularly in Fig. 8 are recessed at 23 at their ends. The ends 24 of the rails 21 fit in the recesses 23 and these ends 24 are in turn recessed as shown at 25. Additional cross members 26 are secured to the rail and to the stiles and these cross members have grooves 27 formed therein aligned with the recessed portions 24 of the rails 21. The members 26 also have longitudinal grooves 28 formed therein.

The various parts of the door body may be secured together in any desired manner as by fasteners 30 and attention is called to the fact that the stiles 20 and cross members 26 are secured to each other at 31. The stiles 20 and rails 21 are secured together at 32 and the members 26 and rails 21 are secured together at 33.

The metallic sheathing for the stiles is shown in Fig. 11 and comprises a hollow rectangular sheath 35 having flanges 36 extending inwardly therefrom. The ends of the sheaths 35 are cut away and portions of these ends are folded inwardly or back on

themselves as shown at 37, these portions forming channels for a purpose hereinafter set forth. The longitudinal ends of the sheath have formed thereon extensions 38 adapted to be folded over the outer edge portions of the members 26 and into the grooves 28 as hereinafter explained.

The sheathing for the rails 21 is illustrated particularly in Fig. 12 and comprises 10 a rectangular hollow sheath 40 having flanges 41 and at its ends inwardly folded portions 42 (see Figs. 7 and 10). The portions 42 also form channels for a purpose hereinafter set forth. The wall 43 of the 15 sheath 40 is recessed or cut away as shown at 44 to provide for the insertion of the connecting member which connects together the sheath 40 and the sheath 35. The wall 43 also has extensions 45, one at each end there- 20 of for reasons hereinafter set forth.

The metallic covering for the door is mounted thereon in the following manner. The sheaths 35 and 40 are spread or opened sufficiently to permit their being placed over 25 the stiles and rails of the door. Referring particularly to Fig. 10 it will be seen that one of the sheaths 35 has been mounted on a stile and that the inturned portions 37 thereof are disposed in the recess 25 of the 30 rail 21 and in the groove 27 of the member 26. The sheath 40 has also been mounted over the rail 21 and member 26 and has its inturned portions 42 disposed in the recess 25 and groove 27. The connector illustrated 35 particularly in Fig. 13 is used to connect together the sheath 35 and sheath 40. This connector comprises a piece of material having its ends 50 folded over toward each other but spaced apart as shown at 51. There 40 are thus formed channels 52 and 53 between the portions 50 and the main or body portion 54 of the connector. This connector is then inserted in the slot 44 formed in the wall 43 of the sheath 40 and secures together 45 the portion 37 of the sheath 35 and the portion 42 of the sheath 40. It will be understood that connectors are used at both sides of the sheath as clearly illustrated in Fig. 10.

When the sheaths have been so mounted 50 the portions 45 of the sheath 40 are forced into the groove 28 of the member 26 as shown particularly in Fig. 5. The portions 38 of the sheath 35 are then bent back upon themselves and forced into the channel 55 formed 55 in the extension 45.

Panels 60 may be secured in any desired manner and one method of securing the panels is illustrated in Figs. 6 and 14. In 60 Fig. 6 the panels are shown as having a wooden core 61 having a metallic covering 62, the two ends of the covering being extended beyond the core and placed in juxtaposed position with reference to the flanges 41 of the sheath 40. These metallic flanges 65 and extensions can then be secured together

in any desired manner by spot welding and if desired, for ornamental purposes, fillers 63 can be secured in the corners between the rails and stiles and the panels.

Particular attention is directed to the means for securing the adjacent portions of the rail sheaths and the stile sheaths as shown in Figs. 8, 9 and 10. From these figures it will be seen that the connections between the sheaths overlap the connections 75 between the rail and stile thereby increasing the rigidity and ruggedness of the construction, and furthermore by reason of the various overlapping parts the joints are made much more firm and effective. It will be 80 understood that the exposed joints such as the connections between the connector and the inturned portions of the sheaths will be filled in with lead, solder or other suitable material so that in the finished door no 85 joints will be seen.

Although one specific embodiment of the invention has been particularly illustrated and described, it will be understood that the invention is capable of modification and that changes in the construction and in the arrangement of the various cooperating parts may be made without departing from the spirit or scope of the invention as expressed 90 in the following claims.

What I claim is:

1. In a structure of the character described, a pair of body members joined together at an angle to each other, a metallic sheath encasing each body member, said sheaths having portions disposed in abutting relation and a connector joining the abutting portions and disposed within the sheaths, one of said sheaths overlapping the joint between said members. 100

2. In a door structure, a stile, a rail secured thereto and having a groove in the outer wall thereof, a sheath encasing said rail and having an extension disposed in said groove and a sheath encasing said stile and having portions extending around the end of the rail and disposed in said groove. 110

3. In a door structure, a stile, a rail secured thereto and having a groove in the outer wall thereof, a sheath encasing said rail and having an extension disposed in said groove and a sheath encasing said stile and having portions extending around the end of the rail and disposed in said groove and engaging said extension. 115

4. In a door structure, a body member, a second body secured thereto at an angle with respect thereto, one member having a longitudinal groove therein, a sheath encasing one member and having an extension in said groove, a sheath encasing the other member and having portions engaging said extension and disposed in said groove. 125

5. In a door structure, a body member, a second body member secured thereto at an 130

- angle with respect thereto, one member having a longitudinal groove in its outer surface, a sheath encasing one member and having an extension pressed into said groove 5 and a sheath encasing the other member and having portions overlapping said first member and pressed into the groove in superimposed relation with respect to the extension in the other member.
- 10 6. In a door structure, a stile, a rail secured thereto, and having a groove in one side wall, the connection between the stile and the groove being located in a position offset from the inner edge of the stile, a sheath encasing said stile and having portions overlapping the rail, a sheath encasing the rail and having portions abutting the stile sheath, and connectors securing together the abutting edges of the stile sheath 15 and the rail sheath.
- 20 7. In a door structure, a stile having a recess at one end thereof, a rail secured to said stile and having its end disposed in the recess of the stile, a sheath encasing the stile and having projecting end portions extending around the rail, a sheath encasing 25
- the rail and having an extension disposed within the end portions of the stile sheath and means for securing said sheaths together. 30
8. In a door structure, a stile, a rail secured thereto and having a groove in the outer wall thereof and grooves in the side surfaces thereof, a sheath encasing the rail and having an extension disposed in the groove in the outer wall thereof and having edges bent back upon themselves and disposed in the grooves in the side surfaces thereof, a sheath encasing the stile having portions extending around the rail and disposed in the groove in the outer edge thereof, said stile sheath also having edges bent back upon themselves and disposed in the grooves in the side surfaces of the rail, and means disposed in the grooves in the side surfaces 35 of the rail connecting the portions of the rail sheath and stile sheath disposed in said grooves. 40
- 45

In witness whereof, I have hereunto set my hand this 19 day of May, 1924.

CHARLES C. PFEIFFER.
